UNITED STATES PATENT OFFICE

152,707

DESIGN FOR AN INK CONTAINER

Raymond O. Letsch, Waterloo, Iowa

Application June 13, 1947, Serial No. 139,671

Term of patent 14 years

(Cl. D74—8)

To all whom it may concern:

Be it known that I, Raymond O. Letsch, a citizen of the United States, residing at Waterloo, in the county of Blackhawk and State of Iowa, have invented a new, original, and ornamental Design for an Ink Container, of which the following is a specification, reference being had to the accompanying drawing, forming a part thereof.

Figure 1 is a perspective view of an ink container, showing my new design.

Figure 2 is a plan view of the article shown in Figure 1 with the cover removed;

Figure 3 is an end view thereof; and

Figure 4 is a side elevational view of the ink container shown in Figure 2.

I claim:

The ornamental design for an ink container, as shown.

RAYMOND O. LETSCH.
